UNITED STATES PATENT OFFICE.

GIJSBERTUS GROENEWEGEN, OF DELFT, NETHERLANDS.

VALVE FOR STEAM ENGINES.

1,422,437.

Specification of Letters Patent. Patented July 11, 1922.

Application filed December 27, 1918. Serial No. 268,488.

To all whom it may concern:

Be it known that I, GIJSBERTUS GROENEWEGEN, a subject of the Kingdom of the Netherlands, residing at Delft, Netherlands, 5 7 Oude Delft, have invented a new and useful Improvement in or Relating to a Valve for Steam Engines, of which the following is a specification.

My invention relates to valves for steam 10 engines, and it has for its object to provide a valve including a rotatable steam distributing device and a valve liner movably associated with the same, such members being provided with ports arranged so that by adjusting the valve liner, steam will be fed 15 through the valve gear in one direction or the other to effect a movement of an engine in one direction or the other.

I will describe one form of valve embodying my invention, and will point out the novel features thereof in claims.

In the accompanying drawings, Fig. 1 is a view showing in longitudinal section one form of valve embodying my invention.

25 Figs. 2 and 3 are views of the valve shown in Fig. 1 with the valve and valve liner in the position to effect a forward movement of an engine.

Fig. 4 is a view similar to Fig. 3, showing 30 the parts in position to effect a reverse movement of an engine.

Fig. 5 is a sectional view showing the parts in position to effect the stoppage of an engine.

35 Referring to the drawings, 1 designates an engine cylinder at the side of which is disposed a steam distributing chamber 2.

The chamber 2 is provided with ports 3 and 4 which effect communication between 40 the cylinder 1 and the chamber for admitting steam to the opposite ends of the cylinder, and to thus effect a reciprocation of the piston in the usual manner. One end of the chamber 2 is closed by an end piece 5 which 45 is provided with a bushing 6. The other end of the chamber 2 is closed by a removable cover 7, which also carries a bushing 8.

As shown in Fig. 1, the chamber 2 is divided into three compartments or chambers 11, 12 and 13 by means of the partitions or walls 9 and 10. By virtue of this construction, the ports 3 and 4 open in the intermediate compartment 12 at opposite points.

55 As shown in Fig. 2, the partitions 14 and

15 divide the ports 3 and 4 into two separate passages 16 and 17, and 18 and 19, respectively.

The steam supply is connected to the end chamber 11, while the exhaust pipe is connected to the chamber 13.

The walls 9 and 10 form a casing in which is rotatably mounted a valve liner 20. To effect a steam tight joint between the valve liner 20 and the walls 9 and 10, the inner 65 edges of the latter are enlarged as shown in Fig. 1, and the wall 9 is provided with a flange 21 against which the liner 20 is adapted to snugly fit.

The valve liner 20 is formed at diametrically opposite points with openings or ports 70 24 or 25, such ports controlling the passage of steam to and from the passages 16, 17, etc.

One end of the valve liner 20 projects beyond the wall 10 and has secured thereto 75 a ring 23 to which is fixed an arm 27 carrying a boss 28.

Formed integral with the boss 28 and projecting from the chamber 2 is a shaft 29, the center line of which coincides with the center line of the valve liner.

80 By virtue of this arrangement, the valve liner 20 may be manually operated by means of the shaft 29. The boss 28 forms a bearing for one end of the shaft 31, such shaft

extending axially through the chamber 2 85 and passing through the bushing 6. The shaft 31 is connected to the crank shaft of an engine in such manner that it rotates at the same speed as the engine. Fixed to the

shaft 31 is a cylindrical valve or steam distributing device 32 which is provided with openings or ports 33 and 34 arranged at

points diametrically opposite one another (Fig. 2) and which are separated by a wall 35 in such a way, that the opening 33 con-

stantly communicates with the steam supply, whereas the opening 34 permanently communicates with the exhaust piping.

The circumferential surface of the steam distributing device 32 fits tightly to the interior wall of the liner 20. In order to obtain this steam tight junction, special

movable parts may be arranged at suitable points and maintained in proper position by the steam pressure.

100 The valve operates as follows:

When the engine is to be operated in the forward direction, the shaft 29 is rotated so as to bring the openings 24 and 25 of the liner 20 into alignment respectively with the 110

inlet and outlet ports 16 and 19. The engine is then set in motion and the shaft 31 rotates in the direction of the arrow shown in Fig. 3 so as to carry the openings 33 and 34 of the distributing valve past said openings 24 and 25 respectively. Assuming that the piston is at its highest position, the admission lead to the passage 16 for the steam supply will have been previously opened, 10 that is to say, the side *e* of the opening 33 of the distributing device 32 (see Fig. 3) will have been moved to the left of the side *a* of the opening 24 of the valve liner 20 a distance sufficient to form the admission lead. 15 At the same time the exhaust must have taken place through the exhaust lead, that is to say, the side *g* of the opening 34 in the valve 32 must have been moved to the right of the side *d* of the opening 25 of the valve liner 20 a distance sufficient to form the exhaust lead.

The admission-steam, which enters through the compartment 11 in the valve or distributing device, passes through the opening 33, the opening 24, the passage 16, and the port 3 above the piston into the cylinder 1. The exhaust steam at the other end of the cylinder end escapes through the ports 4, the passage 19, through the opening 25 in the 20 movable valve liner and through the opening 34 into the exhaust chamber 13 (Fig. 1). The openings 33 and 34 have such dimensions and are so disposed that, in the position of the steam distributing device 32 at the 25 end of the admission stroke of the piston an equal area of each of said openings is at opposite sides of an imaginary perpendicular line passing through the shaft 31 and the middle of the distance between the passages 30 16 and 17 as well as 18 and 19, that is to say, the points *e* and *f*, and *g* and *h* respectively are situated at the same distance from this perpendicular line. Hence it follows, that this symmetry also exists, when the openings 35 24 and 25 are placed in alinement with the passages 17 and 18 respectively, thus rendering the valve reversible.

During the forward movement of the engine, the passages 16 and 19 respectively 50 serve to admit and exhaust the steam, where- as the rate of the supply and outlet depends upon the length of the openings 33 and 34. When it is desired to reverse the direction of rotation of the engine, the shaft 29 is turned 55 so that the openings 24 and 25 of the valve liner 20 are moved into alinement with the passages 17 and 18 respectively as shown in Fig. 4.

The valve liner 20 and the valve or steam 60 distributing device 32 are so constructed, that when the valve stands with the admission lead in position for causing forward movement of the engine and the valve liner 20 is moved to its other extreme position, the valve 32 will give the same admission

lead, but in the opposite direction of rotation. The same is true of the exhaust lead.

Hence it follows, that the steam admission opening 33 is equal to the distance between the inner side of the opening 24 in its extreme positions, plus twice the width of the admission lead. In the same way the exhaust opening 34 is equal to the distance between the inner side of the opening 25 in its extreme position, plus twice the width of the exhaust-lead. After reversing the valve liner 20 to secure a reversal of the engine the different parts will take the positions shown in Fig. 4, the valve 32 now being in its other extreme position, having been moved in the direction indicated by the arrow. The distance between the side *b* of the opening 24 and the side *f* of the opening 33 will control the admission. It is further stated, that when the valve liner 20 is moved so 85 that the openings 24 and 25 are placed in the middle of the space between the passages 17, and 18, all supply and exhaust of steam is completely excluded and the engine stops. This position of the parts is illustrated in 90 Fig. 5. It is evident, that this symmetric position of the steam supply and exhaust openings 33, 34 is of positive influence on the steam distribution, and is therefore of great 95 importance to the invention.

Although I have herein shown and described only one form of valve embodying my invention, it is to be understood that various changes and modifications may be made herein without departing from the 100 spirit of this invention, and the spirit and scope of the appended claims.

I declare that what I claim is:

1. A valve, comprising a casing having a chamber formed therein and provided with a plurality of passages disposed at opposite sides of and in communication with said chamber, said passages being arranged in pairs diametrically opposite each other, a shaft mounted for rotation in one end of said casing and carrying a valve liner having a pair of openings disposed in position to be brought into register with either pair of said passages, a shaft journaled at its opposite ends respectively in one end of the casing 115 and in the end of said first shaft and carrying a valve rotatable within said valve liner, said valve having a pair of chambers one in communication with a source of fluid supply and the other in communication with an 120 exhaust outlet and provided with openings disposed in position to alternately communicate with the openings in said valve liner.

2. In a valve, the combination with a casing having a chamber in communication with a source of fluid supply, a second chamber in communication with an exhaust outlet, an intermediate chamber between said supply and exhaust chambers, and a plurality of 125 passages in communication with said inter- 130

mediate chamber, of a rotatable valve member having a pair of chambers one in communication with said supply chamber and the other in communication with said exhaust chamber, each of said valve chambers being provided with an opening for communicating with said intermediate chamber, and a rotatable member be-

tween said valve and intermediate chamber for controlling said communication. 10

In testimony whereof I affix my signature in the presence of two witnesses.

GIJSBERTUS GROENEWEGEN.
